Fig. 10

FIG. 1 is a perspective view of a collapsible stand embodying my new design with the stand shown erected;

FIG. 2 is a top plan view thereof;

FIG. 3 is a bottom plan view thereof;

FIG. 4 is a front elevational view thereof showing the stand collapsed;

FIG. 5 is a side elevational view thereof showing the stand collapsed;

FIG. 6 is a rear elevational view thereof showing the stand collapsed;

FIG. 7 is a side elevational view thereof showing the stand collapsed, the side shown being the opposite of the side shown in FIG. 5;

FIG. 8 is a perspective view showing the front, top and one side of the stand in its collapsed condition;

FIG. 9 is a view of the stand taken along line 9—9 of FIG. 1; and

FIG. 10 is a view of the stand taken along line 10—10 of FIG. 1.

I claim:

The ornamental design for a collapsible support stand for a slide projector or the like substantially as shown and described.
